UNITED STATES PATENT OFFICE

165,294

FOUNDATION GARMENT

Sabine Levy, London, England, assignor to
Caprice Limited, London, England

Application March 13, 1951, Serial No. 14,472
In Great Britain January 25, 1951

Term of patent 14 years

(Cl. D20--2)

To all whom it may concern:

Be it known that I, Sabine Levy, a British subject, residing at London, England, have invented a new, original, and ornamental Design for a Foundation Garment, of which the following is a specification, reference being made to the accompanying drawing, forming part thereof, in which:

Fig. 1 is a front plan view of a foundation garment showing my new design.

Fig. 2 is a rear plan view thereof.

I claim:

The ornamental design for a foundation garment, as shown.

SABINE LEVY.
